Frank Schaeffler

UNITED STATES PATENT OFFICE.

FRANK C. SCHAEFFLER, OF HUNTINGTON, NEW YORK.

ENVELOP.

1,231,204.

Specification of Letters Patent. Patented June 26, 1917.

Application filed August 19, 1916. Serial No. 115,752.

To all whom it may concern:

Be it known that I, FRANK C. SCHAEFFLER, a citizen of the United States, and resident of Huntington, in the county of Suffolk and State of New York, have invented new and useful Improvements in Envelops, of which the following is a specification.

This invention relates to an envelop of novel construction, which is adapted more particularly to be used between the several departments of larger business concerns. With envelops of this class, it has been customary to deliver the papers from one department in envelops addressed to the other department, which envelops were destroyed upon receipt. Papers from the second department were delivered to the first department in other envelops, which were also destroyed, thus involving a great waste of stationery. By my invention inter-department transactions may be carried on in the same envelops, their construction being such that the address may be readily changed from one department to the other, so that they may shuttle between the same for an indefinite period of time. In this way expenses are reduced, manipulation is simplified, and the accumulation of waste is avoided.

30 In the accompanying drawing:

Figure 1 is a front view of an envelop embodying my invention;

Fig. 2 a similar view showing a different adjustment;

35 Fig. 3 a front view with the flap opened;

Fig. 4 an enlarged longitudinal section of Fig. 1, and

Fig. 5 a similar section of Fig. 2.

The body 1 of the envelop is of oblong or other form and provided with an ungummed foldable closing flap 2 having parallel edges. The front 3 of the envelop is provided with two parallel transverse slits 4, 5, adapted for the reception of flap 2, and forming between them a transverse band 6, integral with the front. This band carries the legend or designation 7 of one of the two inter-departments, between which the envelop is to travel back and forth, the drawing showing

it to be marked, by way of example, with 50 the words "John Jones, Claim Dept."

The body of the flap 2 carries on its front the legend or designation 8 of the second department, which by way of example is shown to read: "Tom Brown, Credit Dept." 55 The correlation of the parts is such that the distance of the legend 7 from the root or hinge of flap 2, is substantially equal to the distance of the legend 8 from such hinge, so that when the flap is closed the legend 8 60 will either overlie or underlie band 6. When the charged envelop is transmitted from the first department to the second department, the end flap 2, is passed through the lower slit 5, i. e. the slit farthest from hinge 9. 65 In this way the body of the flap will overlie band 6, and blanket the legend 7 of the latter while the legend 8 on the flap will be fully exposed (Figs. 2 and 5).

When the charged envelop is returned 70 from the second department to the first department, the end flap 2 is passed through the upper slit 4, i. e. the slit nearest hinge 9. In this way, band 6 will overlie and blanket legend 8, of the flap, while the legend 7 of 75 the band will be exposed (Figs. 1 and 4).

It will be seen that by my invention, the address on the envelop may be changed in a most simple manner, so that the envelop is well adapted for inter-department and similar transactions. 80

I claim:

1. An envelop having a front provided with a pair of slits to form a band, a first legend on said band, a flap adapted to be 85 passed through either one of the slits, and a second legend on the flap, said first named legend being adapted to be blanketed by the flap, while the second named legend is adapted to be blanketed by the band. 90

2. An envelop having a front provided with a pair of slits to form a band, a first legend on said band, a hinged flap adapted to be passed through either one of the slits, and a second legend on the flap, the two 95 legends being arranged at substantially equal distances from the hinge of the flap.

FRANK C. SCHAEFFLER.
